US00D980188S

(12) **United States Design Patent** (10) **Patent No.:** **US D980,188 S**
Bellham et al. (45) **Date of Patent:** **** *Mar. 7, 2023**

(54) **HEADPHONES**(71) Applicant: **GN AUDIO A/S**, Ballerup (DK)(72) Inventors: **Philip Bellham**, Ballerup (DK);
Rasmus Trudslev Pedersen, Ballerup (DK);
Bill Zeng, Ballerup (DK)(73) Assignee: **GN AUDIO A/S**, Ballerup (DK)

(*) Notice: This patent is subject to a terminal disclaimer.

(**) Term: **15 Years**(21) Appl. No.: **29/829,473**(22) Filed: **Mar. 4, 2022****Related U.S. Application Data**

(63) Continuation of application No. 29/738,556, filed on Jun. 18, 2020, now Pat. No. Des. 952,600.

(30) **Foreign Application Priority Data**

Dec. 19, 2019 (EM) 007433701-1-5

Primary Examiner — Paula Allen Greene(74) *Attorney, Agent, or Firm* — Hamre, Schumann, Mueller & Larson, P.C.(57) **CLAIM**

The ornamental design for a headphones, as shown and described.

DESCRIPTION

FIG. 1 is a perspective top view of the headphones.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is a bottom view thereof.

The distal end of the headband, away from the ear piece, is a mirror image left/right.

The features shown in broken lines depict environmental subject matter only and form no part of the claimed design.
